UNITED STATES PATENT OFFICE

2,497,395

RECLINING CHAIR

Roy A. Cramer, Sr., Hickman Mills, Mo.

Application March 4, 1946, Serial No. 651,798

15 Claims. (Cl. 155—116)

1

This invention relates to chairs and particularly those of the reclining back type, the principal object being to provide a chair of this character with a seat movable in coordination with the reclining back so as to provide proper body support throughout change of position of a person when shifting from a substantially erect sitting position to a reclining position.

Other objects of the invention are to provide a chair structure wherein movement of the back and seat conforms to natural movement of a person's body when shifting from a sitting to a reclining position; to provide a structure which utilizes weight of a person for facilitating movement of the back and seat, that is, the weight of the body on the back aids in raising the seat when the person moves to a reclining position and the weight of the body on the seat aids in raising the back when the person desires to return to an upright position; to provide a chair with a spring to assist in return movement of the back and seat when a person of light weight is occupying the chair; to provide means for adjusting the action of the spring; to provide a chair structure wherein the seat shifts forwardly and upwardly as the back moves downwardly so that the pivot point of the body of a person seated in the chair is held in a fixed course; to provide a chair structure wherein the back is connected with the seat by a linkage to effect tilting of the back for supporting the back of a person on moving to reclined position; to provide a reclining back chair with a back adjustable vertically for different-sized persons; to provide springs for raising the back when effecting adjustment of the back for height; and to provide the back with a vertically adjustable head rest which may be manipulated independently of adjustment of the back.

Other objects of the invention are to provide a reclining back chair wherein the cushioning material supporting member is shaped both vertically and transversely in accordance with a person's back so that the cushioning material can be of equal thickness over the entire area thereof; and to provide covers for the back, seat and head rest that are readily removable for laundering or dry cleaning.

Further objects of the invention are to provide a reclining back chair of simple and relatively inexpensive construction; and to provide a chair of this character wherein all main actions are controlled by a single lever.

In accomplishing these and other objects of the invention, I have provided improved structure,

2

the preferred form of which is illustrated in the accompanying drawings wherein:

Fig. 1 is a perspective view of a chair constructed in accordance with the present invention and showing the back in reclining position, the covering plate for enclosing the operating mechanism at one side of the chair being removed for better illustration.

Fig. 2 is a similar view but showing the back in substantially erect position.

Fig. 3 is an enlarged longitudinal section through the chair, the upper portion of the back being shown in elevation.

Fig. 4 is a horizontal section through the back and head rest on the line 4—4 of Fig. 3.

Fig. 5 is a sectional view similar to Fig. 3 but showing the seat in raised position and the back in reclining position.

Fig. 6 is an enlarged fragmentary perspective view partially in section particularly illustrating the latch mechanism for retaining the back and seat in an adjusted position.

Fig. 7 is a horizontal section through the chair and showing the seat removed, but with the position thereof indicated in dotted lines.

Fig. 8 is a fragmentary section through a side of the back support, particularly illustrating the spring for raising the back of the chair relative to the seat.

Fig. 9 is a fragmentary perspective view of the back support, particularly illustrating the latch and lever mechanism for retaining the back in vertically adjusted position.

Referring more in detail to the drawings:

1 designates a chair embodying the features of the present invention and which includes a base 2, a pivoting back supporting means 3, a back 4 tilttable on the back supporting means and a seat 5. The base 2 may be constructed in various manners and of various materials, but is illustrated as composed of tubing, since tubing provides a chair frame of strong, lightweight construction. The base 2 includes laterally spaced side portions 6 and 7, each formed of tubing bent to shape for providing front and rear legs 8 and 9 having the desired contour and interconnected by a rearwardly inclined arm supporting rail 10 and a lower rail 11. The front legs 8 of the sides include an inwardly extending arm 12 cooperating with an arm 13 depending from the rail portion 10 for forming a bracket 14 wherefrom the back support is suspended. The arm 13 preferably extends below the arm 12 and has a bifurcation 15.

55 The side portions of the base are interconnected

across the front at a point below the seat by a transverse bar 16 also of tubular cross section. The side portions of the base are also connected below the seat by a transverse rail 17 having its ends secured substantially to the rails 11 as shown in Figs. 1, 2 and 6. To facilitate mounting of latch mechanism, later described, the rail 17 is preferably of rectangular cross section to provide a substantially flat upper face portion 18 to mount the latch mechanism later described.

Carried on the rails 10 are arm rests 19 and 20 that may be upholstered or covered to conform with the seat and back covering later described. If desired, the side portions of the base may be covered on the inner and outer sides by side plates 21 and 22 engaging the respective sides of the frame sections and having interengaging flanges 23 and 24 extending over the tubing so that the tubing forming the sides of the frame is completely enclosed. In order to accommodate the chair operating mechanism within the enclosures, the outer covering plates 21 are preferably offset outwardly above the lower cross rails 11 as indicated at 25 (Fig. 1).

Pivots connected with each of the bifurcated ends 15 of the arms 13 are arms 26 having lateral terminals 28 extending through arcuate slots 29 that are provided in the inside cover plates 22 of the chair frame. The arms 26 are provided with tongues 30 engaged between the ears of the bifurcated terminals of the arms 13 and are hinged thereto by pivot pins 31. The location of the hinge pins 31 relative to the movable seat 5 and back 4 constitute an important part of the present invention to be hereinafter more fully disclosed.

Fixed to and extending laterally from the rearward sides of the arms 26 are arms 32 having terminals 33 extending laterally through the arcuate slots 29 to cooperate with the terminals 28 for suspendedly carrying the back supporting means 3. The back supporting means includes tubular side members 34 having forwardly curved ends 35 preferably corresponding with curvature of the slots 29 and which are connected with the lateral terminals of the arms 28 and 33 by welding or the like. The other ends of the side members 34 extend upwardly and rearwardly so that they terminate a short distance above the arms of the chair as shown in Fig. 3. The side members 34 of the back support are interconnected by a web 36 having the side edges thereof curved around the side members as at 37 and having flanges 38 secured to the body of the web (Fig. 6). The front edge of the web is similarly curved as at 39 (Fig. 7) about the lateral terminals 28 of the arms 26 and about a yoke-shaped cross member 40 which interconnects the inner ends of the terminals 28 as best shown in Fig. 7, so as to provide a connection for a spring assembly 41, later described. The upper edge of the web terminates at the upper ends of the tubular side members of the support and is rolled inwardly as at 42 (Fig. 9) to form a finished edge.

It is obvious that the back support is pivotally suspended from the side portions of the chair frame and is adapted to swing in an arc when the back 4 of the chair is moved toward a reclining position as later described. Slidably mounted on the back supporting means is a slide or carrier 43 having tubular guides 44 slidable within the tubular members 34 and interconnected by a web 45. The guides have heads 46, each including ears 47 and a pin 48 engaged within the upper open ends of the guides. The pins are permanently at-

tached to the guides and form abutments for the ends of coil springs 49 that have one end housed within the tubular guides and the outer ends within the tubular side members of the back supporting means.

The back 4 includes a pan-like member 50 having substantially parallel side flanges 51 and upper flanges 52 and a lower flange 53 corresponding to the desired shape of the back. The flanges 50 are reinforced by a frame 54 extending therearound and having parallel sides 55 which constitute side tracks for a head rest 56.

Cooperating with the member 50 is an inner member 57 having side flanges 58 (Fig. 4) corresponding with the flanges of the member 50 and co-acting therewith to clamp the marginal edges 59 of the back covering material 60. The pan member 57 is removably secured to the pan-like member 50 by fastening devices such as screws 61.

Attention is directed to the fact that the inner member 57 is shaped longitudinally and transversely to conform with the back of a person whereby the cushioning material 62, for example, sponge rubber or the like, may be of substantially uniform thickness over the area of the back, thereby simplifying the construction and reducing the cost of assembly.

With the back structure thus described, the covering for the cushioning material is readily removable for laundering or dry cleaning simply by removing the fastening devices 61 so that the inner member 57 may be withdrawn to loosen the marginal edges 59 of the covering 60 so that the covering may be readily removed therefrom.

In order that the lower portion of the back is kept in supporting contact with the back of a person during movement thereof, the back is pivotally connected with the ears 41 of the heads 46 by providing the outer back member with lugs 63 having internally threaded sockets registering with openings in the ears 41 to mount trunnions in the form of screws 64. Movement of the back is limited under control of a linkage with the seat 5 and which is later described. In order to anchor the back in any one of its positions, the inner face of the web 36 carries a bracket 65 that cooperates with one of the side members 34 in journaling a rock shaft 66. One end of the rock shaft carries a latching arm 67 having a tooth 68 adapted to engage in any one of a series of openings 69 formed in the web 45 of the slides 43. The opposite end of the rock shaft carries an arm 70 provided with a push button stem 71 which extends rearwardly through a suitable opening in the web 36 of the back support and mounts a push button 72 whereby the shaft 66 may be rocked to effect release of the tooth 68 on the latch arm 67 from engagement with one of the openings 69. The latch arm is normally retained in position to engage one of the openings by a spring 73 having one end attached to the latch arm and the other end to the bracket 65. The web of the slide 43 operates in slots 74 located in the facing sides of the tubular members in which the guides of the slide are mounted.

The head rest 56 includes a frame 75 having a construction substantially conforming to that of the back of the chair so as to retain a cushioning material 76 and a removable covering 77. The frame 75 is carried for vertical movement over the cushioning of the chair back by arms 78 overlapping the sides of the back and having tubular slides 80 engaging the side members 53 of the back frame previously described. The slides 80 are so formed relative to the tracks that the

head rest is frictionally supported in its desired adjusted position.

The seat 5 includes a base plate 81 conforming to the general shape of the seat and having a depending marginal flange 82 extending along the front and sides thereof and terminating in a reversely turned edge 83 for forming a groove 84 to anchor the marginal edge of the seat covering material 85.

The cushioning material 86 for the seat is carried on the base plate and retained in position by the covering 85 that is stretched thereover. The seat is mounted on the frame of the chair for upward and forward movement upon downward swinging movement of the back whereby the movement of the back and seat are coordinated to conform with movement of the body of a person seated in the chair when the person moves to and from reclining position. Such movement of the seat is effected by providing an elevating support on the cross bar 16 including brackets 87 fixed to and extending vertically from the cross rail and having rollers 88 journaled on pins 89. The rollers 88 operate in inclined tracks 90, each including a channel 91 pivoted as at 92 (Fig. 5) to wing-like brackets 93 fixed to and depending from a transverse reinforcing bar 94 attached to the underface of the base plate of the seat. The channel-like guide tracks extend rearwardly and downwardly from their pivot points and the rear ends are adjustably connected with the wing-like brackets to support the tracks at a selected angle relatively to the horizontal so that when the seat is shifted forwardly the forward edge thereof is raised by reason of the channel-like tracks moving upwardly and forwardly over the rollers 88. In order to provide and maintain adjustment of the tracks, the rear ends thereof carry fastening devices such as bolts 95 that extend through arcuate openings 96 in the wing-like brackets and which are adapted to clamp the rear ends of the channel-like tracks against the brackets upon tightening of nuts on the bolts as will be well understood. The rear of the seat is supported on the lateral terminals 28 of the back supporting means by arm-like supports 97 that have their upper ends extending through slots 98 in the base plate 81 of the seat and pivotally secured as at 99 with brackets 100 fixed to the base of the seat. Thus, when the back is moved to a reclining position, the arms 97 being fixed to the terminals 28, lift the rear of the seat and move the seat forwardly.

In order to control tilting of the back on the back support, the seat and back are interconnected by a lost motion connection including a link 101 as above mentioned. The link 101 is pivoted as at 102 at its lower end to an ear-like bracket 103 extending rearwardly from the rear edge of the base of the seat as best shown in Fig. 3. The upper end of the link extends through a slot 104 in the pan-like members of the back and slides in the space 105 (Fig. 3). The spring assembly 41 is to assist a light-weight person in raising the back from reclining position and includes a shoe 106 carrying a tubular stem 107 slidably mounted in a tubular guide 108 having its forward end pivotally supported on the cross bar 16 by a bracket 109 having a portion thereof engaged around the rail and cooperating with the shoe 106 to support the tubular members therebetween. Contained within the tubular members is a coil spring 110 adapted to be tensioned by means of a nut 111.

having threaded connection with a threaded shaft 113 that is journaled within the forward end of the outer tube 108 as indicated at 114. The shaft is provided with a hand wheel 115 whereby the shaft may be rotated to move the nut thereon for adjusting action of the spring 110. It is obvious that by adjusting the spring any desired balancing effect may be maintained to suit the occupant of the chair.

In order to support the back and seat in adjusted position, the arcuate portions of the side members of the back support have racks 116 and 117 fixed to the sides thereof and provided with a series of notches 118 to pass a latch bolt 119 that is slidably mounted on the upper flat face of the transverse rail 17. The latch bolt has upwardly offset ends 120 to register with the notches of the racks, the offset ends of the latch bolt being slidably mounted in guides 121 and 122 located at the desired levels. The guide 122 is supported on a built-up portion 123 of the rail 17 and the guide 121 is mounted on the adjacent longitudinal rail 11 and on a gusset-like plate 124 which mounts a bell crank lever 125. The bell crank lever includes an arm 126 engaged in a notch 127 of the latch bolt so that when the bell crank is rocked on its pivot 128, the latch bolt is reciprocated to effect movement of the outer end thereof out of engagement with the rack 117 and a notch 130 in the top of the bolt into position for registering with the rack 116. When in this position, the back supporting means is free to permit movement of the back to any one of its respective positions as governed by the notches in the racks 116 and 117.

The actuating arm 131 of the bell crank is connected by a link 132 with an actuating lever 133 that is pivotally supported as at 134 on a bracket 135 carried by the longitudinal rail 11 at the right hand side of the chair as best shown in Figs. 1 and 2. The latch bolt is normally retained in position to effect rocking of the back support by means of a coil spring 136 having one end attached to a fixed part of the side frame and its opposite end to the latch release lever 133 at a point between the pivot 134 and its connection with the link 132. The release lever is suitably formed so that the operating end 137 is adapted to project through a suitable slot 138 (Fig. 7) provided in the side cover plate at that side of the chair.

The chair constructed and assembled as described ordinarily has the back thereof raised to the position shown in Fig. 2 and secured by the latch bar. When a person seats himself in the chair, the back is adjusted for height. The back may be raised and lowered to suit the size of the person by releasing the latch 67, responsive to pressing on the button 72 and sliding the back up and down until it is at a comfortable height. During sliding movement of the back, the guides of the slide or carriage move within the tubular members of the back support and when the back is in the desired position, pressure on the latch button is released to permit the spring 73 to move the latch 67 so that the tooth 68 thereof slides into the nearest opening 69 of the web 45.

The head rest is then adjusted to proper height on the back by sliding the guides of the rest along the side members 55 of the back frame.

When it is desired to move to a reclining position, the occupant of the chair grasps the lever 133 and shifts it against action of the spring

136 to rock the bell crank through the link 132. Movement of the bell crank causes the arm 128 thereof to shift the latch bolt 118 so that the notch 130 therein is brought into registry to pass the teeth of the rack 116 and the opposite end of the latch bolt clears the teeth of the other rack. The occupant of the chair may then push against the back so that the back moves toward reclining position. During this movement of the back, the back supporting means swings on the pivot 31 and the terminal of the arms 28 and 32 move forwardly of the arcuate slots 29 which carry the side members and connecting web therewith. The movement effects raising of the seat supports 97 and causes the rear of the seat to raise and shift forwardly on the rollers 88. This movement on the rollers causes the channel-like tracks to raise the forward portion of the seat so that the forward portion raises simultaneously with the rear portion of the seat. Shift of the seat and simultaneous lowering of the back conforms with movement of the body of the person and avoids pull of the chair on any part of the person's body or the customary disarrangement of the person's clothing. Consequently, when the person reaches the desired reclining position, he is comfortably located and there is no necessity of re-arranging his body on the chair.

Attention is directed to the fact that the suspension of the back supporting means from an axis above the seat places the pivot in the path of movement of the hinge joint of the person's body and the space closes between the chair seat and back; consequently, there is no slipping between the person and the surface of the seat or back of the chair.

During movement of the seat, the lower portion of the back tilts upwardly toward the body of the person to provide support therefor. This is effected by the lost motion link connection between the seat and the back.

When the back is in the desired reclining position, pressure on the lever 133 is released so that the spring 134 shifts the latch bolt into position to re-engage the teeth of the racks 116 and 117. During movement of the person to reclining position, pressure on the back assists raising of the seat and lifting of the body by the seat controls downward movement of the back. When it is desired to return to a sitting position, the latch lever is again actuated to release the latch bolt so that weight applied on the seat supplemented by action of the spring 110 returns the back to substantially upright position as shown in Fig. 2.

From the foregoing it is obvious that I have provided a reclining back chair wherein the seat moves in coordination with the back so as to provide proper body support throughout the change of position of a person when shifting from a substantially erect sitting position to a reclining position.

It is also obvious that the movement of the back and seat conforms to the natural movement of a person's body when shifting from a seating to a reclining position and that the weight of the person is utilized in effecting movement of the back and seat, that is, the weight of the body on the back aids in raising the seat when the person moves to a reclining position and the weight of the body on the seat aids in raising the back when the person desires to return to an upright position.

It is also obvious that the present invention is readily adapted for use in any type chair such

as those used in railway coaches, homes, lounges, and airplanes as well as wheel chairs and any chair where comfort is desired.

What I claim and desire to secure by Letters Patent is:

1. A chair including a base, a back, supporting means for said back, means for suspending the back supporting means for swinging movement on the base from a position adapted for supporting the back of an occupant seated in the chair to positions adapted for supporting the back of the occupant when the occupant shifts toward a reclining posture, a seat, seat supporting means on the back supporting means and on said base for raising the seat and moving the seat forwardly when the back supporting means is moved toward said reclining position, means pivotally carrying the back on the back supporting means, and a connection between the back and seat to effect pivotal movement of the back on said supporting means responsive to movement of said seat.

2. A chair including a base, a back, supporting means for said back, means pivoted on the base and having connection with the back supporting means for suspending the back for swinging movement from a position adapted for supporting the back of an occupant seated in the chair to positions adapted to support the back of the occupant when the occupant shifts toward a reclining posture, a seat, seat supporting means on the back supporting means and having connection with the seat for raising the rear of the seat and moving the seat forwardly when the back supporting means is moved toward said reclining position, elevating means for raising the front of said seat simultaneously with forward movement of the seat, a pivotal connection between the back and the back supporting means on which the back is adapted to rock, a connection between the back and seat for controlling said rocking movement, and means for stopping movement of the back supporting means to retain said seat and back relatively immovable on said back supporting means.

3. A chair including a base, a back, supporting means for said back, means having pivotal connection with the base and having connection with the back supporting means for suspending the back supporting means for swinging movement on the base from a position adapted for support of the back of an occupant seated in the chair to positions adapted to support the back of an occupant when shifting toward a reclining posture, a seat, seat supporting means on the back supporting means and having pivotal connection with said seat for raising the rear of the seat and moving the seat forwardly when the back supporting means is moved toward said reclining position, elevating means between the base and said seat for raising the front of said seat simultaneously with forward movement of the seat, means pivoting the back on the back supporting means for rocking movement of the back on a transverse axis and at a point intermediate the height of the back, and a connection between the seat and the back for effecting rocking movement of the back on said pivoted axis when the back is moved toward said reclining positions.

4. A chair including a base having laterally spaced sides, a back, supporting means for said back, means having pivotal support on said sides and having connection with the back supporting means for suspending the back supporting means for swinging movement between said sides of the

base from a position adapted for support of the back of an occupant seated in the chair to positions adapted to support the back of the occupant when shifting toward a reclining posture, a seat intermediate the side portions of the base, seat supporting means on the back supporting means and having pivotal connection with said seat for raising the rear of the seat and moving the seat forwardly between said side portions of the base when the back supporting means is moved toward said reclining position, elevating means between the base and said seat for raising the front of said seat simultaneously with forward movement of the seat, means pivoting the back on the back supporting means for rocking movement of the back on an axis transversely of said back and at a point intermediate the height of the back, a connection between the seat and the back for effecting rocking movement of the back when the back is moved toward said reclining positions, and means for stopping and holding the back supporting means in any of said positions and to retain said seat and back in fixed positions with respect to the back supporting means.

5. A chair including a base, a back, supporting means for said back, means having pivotal support on the base and having connection with the back supporting means for suspending the back supporting means for swinging movement on the base from a position adapted for support of the back of an occupant seated in the chair to positions adapted to support the back of the occupant when shifting toward a reclining posture, a seat, seat supporting means on the back supporting means and having pivotal connection with said seat for raising the rear of the seat and moving the seat forwardly on the base when the back supporting means is moved toward said reclining position, elevating means between the base and said seat for raising the front of said seat simultaneously with forward movement of the seat, a slide connected with said back, means pivotally connecting the back with said slide for rocking the back on the back supporting means, means on the back supporting means for movably supporting the slide to adjust the rocking point of said back with respect to said seat, and means for latching the slide relatively to the back supporting means.

6. A chair including a base, a back, supporting means for said back, means having pivotal support on the base and having connection with the back supporting means for suspending the back supporting means for swinging movement on the base from a position adapted for support of the back of an occupant seated in the chair to positions adapted to support the back of the occupant when shifting toward a reclining posture, a seat, seat supporting means on the back supporting means and having pivotal connection with said seat for raising the rear of the seat and moving the seat forwardly on the base when the back supporting means is moved toward said reclining position, elevating means between the base and said seat for raising the front of said seat simultaneously with forward movement of the seat, a carrier for said back, means for pivoting the back on said carrier for rocking movement of the back on a transverse axis, a connection between the back and seat to rock said back upon movement of the seat, said carrier having movable support along said back supporting means for adjusting the rocking point relatively

10 to said seat, and means for latching the carrier relatively to the back supporting means.

7. A chair including a base having laterally spaced sides, a back, supporting means for said back and having tubular side members, means pivoted on said sides and having connection with the side members of the back supporting means for suspending the back supporting means for swinging movement between said sides of the base from a position for supporting the back of an occupant of the chair when seated to positions adapted to support the back of the occupant when shifting toward a reclining posture, a seat intermediate said side portions of the base, seat supporting means on the back supporting means and having connection with said seat for raising the rear of the seat and moving the seat forwardly between said side portions of the base when the back supporting means is moved toward said reclining position, elevating means between the base and said seat for raising the front of said seat simultaneously with forward movement of the seat, a back carrier having tubular guides slideable within the tubular side members of the back supporting means for adjustment of the back vertically with respect to said seat, pivot means connecting the back with said tubular guides for rocking movement of the back on a transverse axis at a point intermediate the height of the back, springs housed within said tubular guides and side members for urging the carrier in a direction to assist raising of the back, and a latch for retaining the carrier in a selected position on the back supporting means.

8. A chair including a base, a back, supporting means for said back, means pivotally connected with the base and having connection with the back supporting means for suspending the back supporting means for swinging movement from a position adapted for supporting the back of an occupant when seated in the chair to a position adapted to support the back of the occupant when shifting toward a reclining posture, a seat on the base, means for raising said seat and shifting the seat simultaneously with movement of the back supporting means, a carrier for the back and movable on the back supporting means to and from said seat, means for pivoting the back on said carrier for rocking movement of the back on a transverse axis, resilient means carried by the back supporting means for urging the carrier in a direction to assist in raising the back, control means having connection with said seat and sliding connection with the back for controlling rocking movement of the back in the various positions of the carrier, and latch means between the carrier and the back supporting means for retaining the carrier in a selected position on the back supporting means.

9. A chair including a base, a back, supporting means for said back, means pivotally connected with the base and having connection with the back supporting means for suspending the back supporting means for swinging movement on the base from a position adapted for supporting the back of the occupant seated in the chair to positions for supporting the back of the occupant when shifting toward a reclining posture, a seat on the base, a back carrier connected with said back and movable on the back supporting means for adjustment of the back vertically with respect to said seat, means pivoting the back on the carrier for rocking movement of the back on a transverse axis, resilient means for urging the

carrier in a direction to assist in raising the back, control means having connection with said seat and sliding connection with the back for controlling rocking movement of the back in the various positions of the carrier, and a latch means for retaining the carrier in a selected position on the back supporting means.

10. A chair including a base having laterally spaced sides, a back, supporting means for said back including laterally spaced tubular members having ends curving downwardly and forwardly between sides of the base, means for pivotally connecting the curved ends of said members with the sides of the base for suspending the back supporting means for swinging movement between said side portions of the base from a position adapted for supporting the back of an occupant when seated in the chair to a position adapted to support the back of the occupant when the occupant shifts toward a reclining posture, a seat intermediate said side portions of the base, seat supporting means on the curved ends of the tubular members and having pivotal connection with the seat for raising the rear of the seat and moving the seat forwardly between said sides of the base when the back supporting means is moved toward said reclining position, elevating means between the base and said seat for raising the front of said seat simultaneously with forward movement of the seat, guides in the upper ends of said tubular members, a web connecting the guides, means for pivotally mounting the back on said guides, springs in the tubular members and engaging the guides to raise the back, a spring connecting the back supporting means with the base for assisting in raising the back supporting means and returning the seat when the occupant shifts from reclining to sitting posture, and a lost motion connection between the seat and back to control pivotal movement of the back on said guides.

11. A chair including a base, seat and back members, means for mounting said members on the base for alternately lowering one of said members and raising the other on the base responsive to shifting weight of an occupant when in said chair, a rocking support for the back on said back mounting means, control means for controlling rocking movement of the back relative to said seat, and a spring connecting one of the members with the base for facilitating movement of said members.

12. A chair including a base having laterally spaced sides, a back, supporting means for said back having side members provided with downwardly and forwardly curving ends positioned between said sides, arms having fixed connection with said side members and extending substantially radially with respect to the curvature of said ends and having pivotal connection with the sides of the base on the axis of curvature of said members for suspending the back to swing between the sides of the base from a position adapted to support the back of an occupant seated in the chair to positions adapted to support the back of the occupant when the occupant shifts toward reclining posture, a seat intermediate said side portions of the base and located above said curved ends of the back supporting means, and seat supporting means connecting terminals of said curved ends of the back supporting means with the seat for raising the seat and projecting the seat forwardly between said sides of the base when the back supporting means is moved toward said reclining position.

13. A chair including a base having laterally spaced sides, a back, supporting means for said back having side members provided with downwardly and forwardly curving ends positioned between said sides, arms having fixed connection with said side members and extending substantially radially with respect to the curvature of said ends and having pivotal connection with the sides of the base on the axis of curvature of said members for suspending the back to swing between the sides of the base from a position adapted to support the back of an occupant seated in the chair to positions adapted to support the back of the occupant when the occupant shifts toward reclining posture, a seat intermediate said side portions of the base and located above said curved ends of the back supporting means, seat supporting links connecting terminals of said curved ends of the back supporting means with the seat for raising the seat and projecting the seat forwardly between said sides of the base when the back supporting means is moved toward said reclining position, an arcuate rack on the curving end of at least one of said side members, and latch means for engaging teeth of said rack to support the back and seat members in a selective position.

14. A chair including a base having laterally spaced sides, a back, supporting means for said back having side members provided with downwardly and forwardly curving ends positioned between said sides, arms having fixed connection with said side members and extending substantially radially with respect to the curvature of said ends and having pivotal connection with the sides of the base on the axis of curvature of said members for suspending the back to swing between the sides of the base from a position adapted to support the back of an occupant seated in the chair to positions adapted to support the back of the occupant when the occupant shifts toward reclining posture, a seat intermediate said side portions of the base and located above said curved ends of the back supporting means, seat supporting links connecting terminals of said curved ends of the back supporting means with the seat for raising the seat and projecting the seat forwardly between said sides of the base when the back supporting means is moved toward said reclining position, a yoke-shaped cross member connecting said curved ends of the side members, a cross member connecting the sides of the base forwardly of said yoke-shaped member, telescoping tubes pivotally connecting said yoke-shaped member with the cross member, a coil spring housed within said tubes, and a threaded shaft rotatably mounted in one of said tubes having an abutment for engaging one end of said spring to control action of the spring for regulating movement of the back carrying means under weight of the occupant.

15. A chair including a base having laterally spaced sides, a back, supporting means for said back having side members provided with downwardly and forwardly curving ends positioned between said sides, arms having fixed connection with said side members and extending substantially radially with respect to the curvature of said ends of the side members and having pivotal connection with the sides of the base on the axis of curvature of said members for suspending the back to swing between the sides of the base from a position adapted to support the back of an occupant seated in the chair to positions adapted to support the back of the occupant when the occupant shifts toward reclining posture, a seat intermediate said side portions of the base and located above said curved ends of the back supporting means, seat supporting links connecting terminals of said curved ends of the back supporting means with the seat for raising the seat and projecting the seat forwardly between said sides of the base when the back supporting means is moved toward said reclining position, an arcuate rack on the curving end of at least one of said side members, and latch means for engaging teeth of said rack to support the back and seat members in a selective position.

13

occupant shifts toward reclining posture, a seat intermediate said side portions of the base and located above said curved ends of the back supporting means, seat supporting links connecting terminals of said curved ends of the back supporting means with the seat substantially forwardly of the rear of the seat for raising the seat and projecting the seat forwardly between said sides of the base when the back supporting means is moved toward said reclining position, and means for simultaneously raising the front of the seat.
